UNITED STATES PATENT OFFICE

LAWRENCE F. OTTEN, OF FORT THOMAS, KENTUCKY, AND GEORGE D. CULLIS, OF EVANSTON, ILLINOIS, ASSIGNORS TO THE WADSWORTH WATCH CASE CO., OF DAYTON, KENTUCKY, A CORPORATION OF KENTUCKY

TWIN FOLD FOR BRACELETS

Application filed July 15, 1929. Serial No. 378,290.

Our invention relates to fastening means for bracelets such for example as are used with wrist watches, and is related to that type of fastener in which a continuous bracelet portion is shortened so as to clasp snugly the wrist of the user, by means of a toggle arrangement.

Hitherto in continuous clasps for bracelets it has been usual to terminate one side of the strap, mesh fabric band or the like in a plate curved to fit the under side of the wrist, and then to hinge or connect the other end of the band to the plate by means of a link or toggle arrangement such that when the bracelet 15 clasp is closed the toggles or links cause a portion of the said band to lie above the plate, thereby shortening the effective diameter of the band. This construction has in general been somewhat cumbersome in that it has a 20 comparatively great throw, is not adjustable, and precludes the use of a cap over the plate and toggles excepting a cap of such large size as will practically cover the said plate. Such a cap is unwieldy. Furthermore the clasp 25 itself could only be operated from one side.

It is the object of our invention to provide a clasp which will have a balanced appearance, which can be opened from either side, and which may and preferably is provided 30 with a central cap of small size and attractive in its proportions.

Another object of our invention is the provision of means whereby the clasp may be opened from either side by a pull upon a cap 35 or equivalent member which acts as a toggle.

Additional objects of our invention are the provision of a clasp which will be easier to adjust and in which all parts for adjustment are concealed; the provision of a clasp in 40 which the relation of parts is symmetrical and in which means may be provided for taking up a length of the band, strap or mesh which forms the bracelet proper, on both sides of the clasp so that the clasp may be located 45 at the proper position in the circumference of the bracelet with reference to a watch or the like, without the provision of cumbersome means adjacent the watch itself for such adjustment.

These and other objects of our invention

which will be pointed out hereinafter or will be apparent to one skilled in the art upon reading these specifications, we accomplish by that certain construction and arrangement of parts of which we will now describe a preferred embodiment, reference being had to the drawings which accompany this specification.

In the drawings:

Figure 1 is a plan view of our clasp in open 60 position.

Figure 2 is a side elevation thereof.

Figure 3 is a plan of our clasp with one of the wings closed.

Figure 4 is an elevation of our device in 65 the position of Figure 3.

Figure 5 shows in plan our clasp closed.

Figure 6 is an elevation showing our clasp as it is being opened, from what we term the inverse direction, the view illustrating the 70 action of the cap as a toggle.

Figures 7, 8 and 10 are respectively a plan view, an end elevation and a side elevation of the base 7 of our clasp.

Figure 9 is a view thereof partly in a section taken along the line A—A of Figure 7.

Figure 11 shows a side and end elevation, the tooth attachment member which we use in attaching a length of chain mesh, strap, 75 band or the like to our clasp.

Figure 12 shows in plan and side elevation, the cap toggle member or wing of our device.

Figure 13 shows in plan and in side elevation, the other toggle member or wing of our clasp.

Figure 14 shows in plan and elevation the cap proper.

Figure 15 in plan and end elevation shows the attachment member which we use in our clasp.

Figure 16 is the cap plate in plan and end elevation.

Figure 17 is a sectional view of the cap assembly of our device.

Broadly our invention comprises a base plate adapted to be placed in a desired position upon the wrist of the wearer, and having on either end toggles or wings to which the band of the bracelet is attached, which wings fold over on top of the base plate, to 95 100

either with a cap hinged on the outer end of one of the wings, and appropriate means for locking the structure in clasped position.

In the several views, the base plate indicated at 1 is shown having a central depression 2, the purpose of which is both to give additional strength to the structure and to accommodate the wings or toggles hereinafter to be described. Flanges 3 are bent up on either side of the plate so as to give it a trough shape, and the entire plate is curved appropriately to fit the wrist of a wearer. For additional strength, ribs or corrugations 4 may be struck from the bottom of the plate, and are preferably made to extend downwardly, leaving grooves within to accommodate corresponding ridges or corrugations struck in the wings or toggles. The ends of the base plate extend somewhat beyond the termination of the depressed portion 2 and are bent over to form knuckles 5, being part of the hinge construction by which the toggles or arms are pivoted to the base plate. The termination of the depressed portion 2 short of these knuckles leaves room for the corresponding knuckle portions upon the wings or toggles next to be described.

Toggles 6 and 7 are hinged to either end of the base plate. The toggles are designed to be folded over in sequence, the right hand toggle as shown in the several figures being the one which folds over first. The left hand toggle 6 is the toggle which holds the cap presently to be described, which cap covers the meeting line of the two toggles. The toggles are of a width preferably to permit their falling, in clasped position, in a depressed portion 2 of the base plate; and for stiffening they may have reinforcing ribs or corrugations 8 struck from their surfaces longitudinally and adapted to fall within the corrugations 4 in the base plate so as to give a compact structure when the clasp is closed. Upon one end of the wing or toggle 7 there will be formed a hinge knuckle 9 adapted to be placed between the knuckles 5 on the right hand end of the base plate 1, and there to be held by a hinge pin 10. The toggles will both be appropriately curved to conform to the base plate. Upon the outer end of the toggle 7 an additional hinge knuckle 11 is formed by turning over the metal, and this knuckle is used to form a hinge with a band attachment member shown in Figure 15.

The band attachment member comprises a U-shaped clamping portion 12, one edge of which is turned over within, as at 13, and which is provided with hinge knuckles 14. The knuckles 14 and 11 are held in hinge-forming relationship by means of a hinge pin 15 terminating in rounded ends as most clearly shown in Figure 1 at 16. The knuckles 14, extending beyond the hinge knuckle 11, bring the width of the band at-

tachment device substantially equal to the width between the flanges 3 of the base plate; and the rounded portion 16 of the pin 15 lying somewhat beyond the knuckles 14 adapted to enter between the flanges 3 only somewhat against the spring tension thereof. A locking construction is formed by peening out depressions 17 in the flanges 3, in which depressions the rounded end 16 of the hinge pin may seat. The closed relationship of the toggle 7 and the base plate is shown in Figures 3 and 4; and the manner of operation of the lock will be clear. Preferably there is provided a means for fastening the band, mesh fabric, strap or the like used in the bracelet, into the clamp portion 12 in such a way that adjustment may be had by shortening the band. To accomplish this, we preferably make use of the toothed member 18 of Figure 11 which is a strip of metal of a length substantially equal to the width of the band, one arm of the U being formed into teeth 19. These teeth are pressed into a band or strap or caused to enter the spaces between links in a mesh fabric 20 whereupon the end of the band or fabric and the member 18 are inserted together endwise into the clamp 12. The turned over portion 13 of the clamp engages the member 18, and the band or fabric cannot be withdrawn longitudinally. When it becomes necessary to alter the length of the band, it may be removed endwise from the clamp 12, a portion cut off and the member 18 replaced thereon in a new position. Our clasp is such that when it is in closed position the clamps 12 are not only hidden, but are in such a position that nothing can be removed from them endwise. The particular adjustable mechanism just described is not a part of our present invention. It has other utility than in our device, nor is our device restricted to its use. The band or fabric may be otherwise fastened into our member 12, or a different type of member provided such as one into which a mesh fabric may be soldered. The link 6 is generally similar in construction to the wing 7, and has a knuckle 21 to be held in hinge-forming relationship with the knuckles 5 on the left hand end of the base plate by means of a pin 22 as will be readily understood. The knuckle 23 on the other end of the toggle 6 is, however, shorter than the corresponding knuckle 9 on the toggle 7, for the reason that room must be left in the construction for the assembly of a hinge from the knuckles 5, the knuckle 23 and knuckles 24 on the cap or upon a member attached thereto. We use upon the end of the toggle 6 another of the clamp members 12 as shown in Figure 15 having hinged knuckles 14.

Next we provide a cap indicated generally at 25 to cover the juncture between the wings or toggles when in clasped position, to serve

as a lock and an opening toggle, and for other purposes as will hereinafter be made clear. It also is hinged to the end of toggle 6, as may be done if desired by soldering 5 knuckles 24 to the cap 25. What we prefer to do however is to provide a cap plate 26 having a raised portion 27 in the mid portion thereof, to which the knuckles 24 are soldered. The cap plate is adapted to fit 10 within the cap 25 and it may have turned over edges 28 lying along the sides 29 of the cap plate. Portions of the metal 30 of the cap are then turned over to clamp the cap plate in position. The cap itself may of 15 course be engraved or ornamented as desired. The projection 27 in the cap plate is slightly off center toward the left in the several figures, so that the meeting line between the two wings or toggles in folded over position 20 will fall centrally of the cap. This enables us to position the cap centrally of the base plate. This construction will be clear from a consideration of Figure 17. The hinge knuckles 5 on the left hand end of the base 25 plate, the knuckle 23 on the toggle 6, and the knuckles on the cap plate 26 are assembled into hinge forming relationship by means of a hinge pin 31. This hinge pin may also terminate in rounded projections 30 and be caused to lock inside peened out projections 32 in the base plate; although this is optional because the cap also is arranged so as to lock upon the projections 17 and 32. Side members 33 are provided upon the cap, 35 which are adapted to lie outside the flanges 3 upon the base plate, and these side members are made wider than the end members 29 so that they will partially extend down along the outside of the flanges 3. Peened out projections 32a and 17a are formed in these side members so as to lock over the projections 32 and 17, thus forming a structure adequately secured.

It will now be clear from an examination of 45 Figure 5 that when our clasp is in closed position all that is visible of any mechanism for the purpose is the cap 25 and the thin flanges 3 of the base plate. Our construction is furthermore secure because not only are the 50 wings or toggles 6 and 7 locked in position as hereinbefore described, but any pull upon the band or mesh 20 will be along the line of the toggles and will have practically a negligible component tending to pull these toggles outwardly from the base plate. The upper portions of the knuckles 5 are made so as to be practically in alignment with the body of the base plate, whereby we achieve a construction in which a ridge in the band or fabric 20 marking the end of the base plate is eliminated. In opening the bracelet the cap 25 may be pulled up from either side. If pulled up from the right side, it will be rigid with the toggle 6 and will tend to lift that toggle 55 away from the base plate. If pulled up from

the left hand or inverse side, it will act as a toggle as shown in Figure 6, in which a movement of the cap 25 in the direction of the arrow will force the toggle 6 outwardly, the cap forming a lever with a sliding fulcrum 70 against the flanges 3. The other ends of the band or fabric portion 20 may be soldered into holders 34 equipped with the usual spring pins for engagement with the band arms 35 of a watch 36.

Various modifications in our invention may be made without departing from the spirit thereof.

Having thus described our invention, what we claim as new and desire to secure by Letters Patent, is:—

1. A clasp for a bracelet comprising a base plate, toggles hinged to said base plate at either end, and means for fastening a band to said toggles, a cap hinged to the outer end of one of said toggles and adapted when said toggle lies above said base plate to cover the meeting line of said toggles thereon.

2. A clasp for a bracelet comprising a base plate, toggles hinged to said base plate at either end, and means for fastening a band to said toggles, a cap hinged to the outer end of one of said toggles and adapted when said toggle lies above said base plate to cover the meeting line of said toggles thereon, and means for locking said cap upon said base plate.

3. A clasp for a bracelet comprising a base plate having upstanding flanges, the central portion of said base plate being depressed 100 for the reception of toggles, extensions on said base plate at either end forming pivoting means for toggles, a pair of toggles pivoted on the ends of said base plate and adapted to fold into said depression, means for pivotally attaching the ends of a bracelet band to the outer ends of said toggles, a cap pivotally attached to the outer end of one of said toggles, and means for engaging said cap with the flanges of said base plate.

4. A clasp for a bracelet comprising a base plate having upstanding flanges, the central portion of said base plate being depressed for the reception of toggles, extensions on said base plate at either end forming pivoting 115 means for toggles, a pair of toggles pivoted on the ends of said base plate and adapted to fold into said depression, and means for pivotally attaching the ends of a bracelet band to the outer ends of said toggles, a cap pivotally attached to the outer end of one of said toggles, and means for engaging said cap with the flanges of said base plate, said means for attaching said bracelet band having means 120 permitting the adjustment of the length thereof.

5. In a bracelet clasp, a base plate having upturned longitudinal flanges and a central depression to receive toggles in folded over position, the ends of said base plate being ex- 130

tended and turned over to form hinge knuckles; a toggle of a width to lie within the said depression having the ends thereof bent over to form hinge knuckles, one of said ends pivoted to the hinged knuckles upon one end of said base plate, the other of said knuckles pivoted by a pin to means for the attachment of a bracelet band, a second toggle of a width to lie within the said depression having its ends turned over to form hinge knuckles, one of said knuckles pivoted to the hinge knuckles on the other ends of said base plate, the other of said knuckles pivoted by a pin to means for the attachment of a bracelet band and also to means affixed to a cap, said toggles adapted to meet substantially centrally of said base plate when in folded over position, said cap adapted to cover the meeting line of said toggle.

20 6. In a bracelet clasp, a base plate having upturned longitudinal flanges and a central depression to receive toggles in folded over position, the ends of said base plate being extended and turned over to form hinge knuckles, a toggle of a width to lie within the said depression having the ends thereof bent over to form hinge knuckles, one of said ends pivoted to the hinged knuckles upon one end of said base plate, the other of said knuckles pivoted by a pin to means for the attachment of a bracelet band, a second toggle of a width to lie within the said depression having its ends turned over to form hinge knuckles; one of said knuckles pivoted to the hinge knuckles on the other ends of said base plate, the other of said knuckles pivoted by a pin to means for the attachment of a bracelet band and also to means affixed to a cap, said toggles adapted to meet substantially centrally of said base plate when in folded over position, said cap adapted to cover the meeting line of said toggle, and means for locking said parts in clasped relationship.

45 7. In a bracelet clasp, a base plate having upturned longitudinal flanges and a central depression to receive toggles in folded over position, the ends of said base plate being extended and turned over to form hinge knuckles, a toggle of a width to lie within the said depression having the ends thereof bent over to form hinge knuckles, one of said ends pivoted to the hinge knuckles upon one end of said base plate, the other of said knuckles pivoted by a pin, means for the attachment of a bracelet band, a second toggle of a width to lie within the said depression having its ends turned over to form hinge knuckles, one of said knuckles pivoted to the hinge knuckles on the other ends of said base plate, the other of said knuckles pivoted by a pin to means for the attachment of a bracelet band and also to means affixed to a cap, said toggles adapted to meet substantially centrally of said base plate when in folded over posi-

tion, said cap adapted to cover the meeting line of said toggles, and means for locking said parts in clasped relationship, said means comprising means on said flanges for engaging at least one of said pins, and means on said cap for engaging said flanges. 70

8. A clasp for a bracelet comprising a base plate, plates hinged at each end of said base plate, and flexible bracelet material secured to the other ends of said hinged plates, 75 and a joint concealing plate hinged to one at least of said hinged plates at its unhinged end.

9. A clasp for a bracelet comprising a base plate, plates hinged at each end of said base plate, and flexible bracelet material secured to the other ends of said hinged plates, and a joint concealing plate secured to one of said hinged plates at its unhinged end. 80
